CLAIM

We claim the ornamental design for a linear trim section, as shown and described.

DESCRIPTION

FIG. 1 is a perspective view of a linear trim section embodying our design;

FIG. 2 is a front view of FIG. 1, the rear being a mirror image thereof;

FIG. 3 is a top view of FIG. 1; and

FIG. 4 is a cross section taken along the line 4—4 in FIG. 3, showing a contour of the top surface.

FIG. 5 is a perspective view of a linear trim section of a second embodiment embodying our design;

FIG. 6 is a front view of FIG. 4, the rear being a mirror image thereof;

FIG. 7 is a top view of FIG. 4; and,

FIG. 8 is a cross section taken along the line 7—7 in FIG. 7, showing a contour of the top surface.

The dashed lines in FIGS. 1—8 are to show the environment and do not form a part of the present invention.

The claimed design is broken on the ends to indicate indefinite length.
